(57) CLAIM

The ornamental design for a medical X-ray imaging apparatus, as shown and described.

DESCRIPTION

FIG. 1 is a top, front and left side perspective view of a medical X-ray imaging apparatus showing my new design; FIG. 2 is a top, rear and left side perspective view thereof; FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a front elevational view thereof in a state that the operation panel faces forward upon being rotated about a first rotational axis and a second rotational axis, the first rotational axis being provided between a supporting column and a connecting section and the second rotational axis being provided between the connecting section and the operation panel;

FIG. 10 is an enlarged perspective view thereof, in which an X-ray irradiation device and the like are omitted;

FIG. 11 is an enlarged perspective view thereof in a state that the operation panel faces forward upon being rotated about the first rotational axis and the second rotational axis;

FIG. 12 is a top, rear and left side perspective view thereof, showing a state that an electronic cassette is put in a housing section disposed at the back of a main body; and,

FIG. 13 is an enlarged view of an operation screen provided to the operation panel in a manner of use.

The broken line portions of the X-ray imaging apparatus throughout the drawings are shown to illustrate environment only and form no part of the claimed design.
